Primary Examiner — Cynthia Ramirez*Assistant Examiner* — Michael A Maharajh(74) *Attorney, Agent, or Firm* — ScienBiziP, P.C.(57) **CLAIM**

The ornamental design for facial blemish removing devices, as shown and described.

DESCRIPTION

FIG. 1 is a first perspective view of facial blemish removing device showing my new design;

FIG. 2 is a second perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is another first perspective view of the facial blemish removing device shown in an alternate configuration.

The broken lines in the drawings are for the purpose of illustrating portions of the facial blemish removing device, which form no part of the claimed design.

1 Claim, 9 Drawing Sheets(56)
